UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed May 9, 1925. Serial No. 29,001.

This invention relates in general to automatic telephone systems, but more particularly to small private installations, and its principal object is to provide a common talking, selective signaling system which is an improvement over the one described in Patent No. 1,665,466, issued to Middleton on April 10, 1928. More specifically, the principal object of the invention is to provide an efficient, yet inexpensive system for private installations, comprising a common talking line with a plurality of substations thereon, a connector switch to furnish individual or selective signaling, a normally inoperative power plant having a dry-cell starting battery and motor generator carrying set to furnish the necessary switching and talking current, a vibrator controlled impedance coil to furnish signaling current, and a code call machine to sound any one of ten different codes twice and then be automatically cut off. Another object of the invention is to provide a new and improved direct line system, comprising two individual lines, and a relay group to control the signaling and talking circuits. This system is used in conjunction with the above described common talking, selective signaling system to relieve it, and has access to the same power plant.

The means by which the foregoing and other objects are accomplished will be fully set forth hereinafter, reference being made to the accompanying drawings, of which Fig. 1 is a circuit diagram of two subscribers' telephones A and E on the common line, connector H, and code call machine CC; while Fig. 2 is a circuit diagram of the subscribers' telephones A' and E' on the direct line, relay group R, and power plant equipment P.

Referring to Fig. 1, the telephones A and E are of the usual automatic type and are connected in bridge of a single pair of talking conductors.

The common line conductors of the substations are connected to the line relay of the connector, which is mechanically of the well known vertical and rotary type of switch and has its bank contacts arranged in horizontal rows or levels. All the contacts in the bank are adapted to be engaged by the wiper 71. The contacts, such as 72, in one of the lower levels of the bank are connected to the individual signaling conductors, such as 65, extending to the several substations, such as E.

These contacts may be in any one of the first nine levels. The contacts, such as 73, in the upper or tenth level of the bank are connected to conductors, such as 74, extending to one set of bank contacts of the code call machine CC.

The code call machine CC consists, essentially, of two sets of banks and associated wipers 86 and 87, a plurality of relays and a motor magnet 85 for controlling and stepping same, and a double coil magnet 84 for controlling the circuits of the code call bells, such as 98 and 99. The machine is mechanically of the rotary type of switch of which the wipers have a home position and move in a forward direction only. The contacts of one bank are grounded; while the contacts of the other bank are connected in pairs to the contacts in the upper level of the connector bank so as to produce ten codes, represented by the ten contacts, sound any code twice, and then automatically be cut off.

Referring to Fig. 2, the telephones A' and E' are of the usual manual type and are located at the same places as the automatic telephones A and E of Fig. 1. The line of telephone A' when calling is connected with the line of telephone E', or vice versa, by the relay group R, which consists merely of a plurality of relays and one condenser.

The power equipment P consists essentially of a motor-generator set, a twenty dry-cell battery B, a circuit breaker 141, a vibrator 142, and an impedance coil 143. The battery B is used to supply current for the switchboard temporarily and among other things, pulls up starting relay 32, Fig. 1, when a receiver is removed, which starts the motor-generator set. The generator builds up to a current output beyond that of the dry cells, is connected in parallel therewith by relay 141, and thus carries the entire switchboard load and also serves to reverse the current through the dry-cells and prolong their life. Relay 141 serves as a circuit breaker when the generator dies down, after all receivers are replaced. Substation ringing current consists of a series of discharge kicks from the impedance coil 143 which is controlled by the vibrator 142.

While separate ground connections and batteries, such as grounded contact 39 of line relay 23 of connector H and grounded battery of said relay, are shown for convenience

throughout the drawings; it will be readily understood that in actual practice there is a common ground potential used and only one source of current used at any one time, such 5 as starting battery B or carrying generator GEN. of the power equipment P. The battery feed conductors 148 and 149 are shown leading to the negative and positive bus bars, respectively, of the switchboard to supply the 10 current therefor.

The utility of a telephone system of the above nature obtains, for example, in the case of a school where there are a large number of subscribers having a very low calling rate. 15 The subscribers can have economical and efficient inter-communicating telephone service with individual and code call signaling. In the case of two subscribers, such as the principal and his assistant, having occasion to 20 converse with each other frequently, a direct line is extended between the subscribers whereby they can signal and converse by using the same power equipment without tying up the common talking line. They are provided with separate telephones or, if found more desirable, one telephone could be used having separate bells and a switch for switching from one line to the other.

Having given a brief description of the apparatus, the operation of same will now be 30 explained more in detail. For this purpose it will be assumed that the subscriber at station A desires to call the subscriber at station E, on the common talking line, and that the 35 latter line is idle. In order to do this, the subscriber at station A removes his receiver and dials the number of station E.

When the receiver is removed at substation A, line relay 23 energizes over a circuit 40 from ground, armature 57 and its resting contact, lower winding of line relay 23, line conductor 21, substation A with the receiver, transmitter, and calling device in bridge of the line, line conductor 22, upper winding of 45 line relay 23 to battery. Upon energizing, line relay 23 closes a circuit for slow to release relay 24 at armature 39, which circuit may be traced from ground, armature 54 and its resting contact, release relay 24, armature 50 39 and its working contact, and vertical magnet 33 to battery. Vertical magnet 33 is not energized at this time on account of the high resistance of release relay 24. Release relay 55 24, upon energizing, opens a point in the circuit of release magnet 35 at armature 42; prepares a circuit for slow to release relay 25 in series with vertical magnet 33 at armature 41; and closes a circuit for starting relay 32 at armature 40, which relay energizes to close 60 a circuit for the busy lamp L and start the motor-generator set in operation to supply carrying current for the switch-board, as will be explained hereinafter.

When the calling subscriber operates his 65 calling device for the first digit in the de-

sired number, which it will be assumed is 2 in the present instance, line relay 23 de-energizes a corresponding number of times. Each time armature 39 of line relay 23 breaks away from its working contact, the initial circuit of release relay 24 is opened. Release relay 24, however, does not deenergize at this time but is maintained energized over a circuit which, before the off normal springs have shifted, is as follows: ground, armature 54 and its resting contact, release relay 24, armature 41 and its working contact, normally closed contact and off normal spring 37, series relay 25, and vertical magnet 33 to battery. Series relay 25, however, 70 does not energize in series with relay 24 on account of the high resistance of the latter. Each time armature 39 comes into engagement with its resting contact, it short circuits release relay 24, whereupon vertical 75 magnet 33 and relay 25 energize in series, release relay 24, being maintained energized during this time by its short circuited winding which makes it slow acting. Each time armature 39 is attracted, the shunt is removed from release relay 24 as soon as armature 39 breaks away from its resting contact and vertical magnet 33 immediately deenergizes. Series relay 25, however, receives 90 some current in series with relay 24 which assists in holding it up, the action being explained in Patent No. 1,671,791, issued May 29, 1928, to R. F. Stehlik. Each time armature 39 comes into engagement with its working contact, series relay 25 is short circuited. 100 It is held up for an interval, however, by its short circuited winding and, consequently, remains energized throughout the series of de-energizations of line relay 23. By the operation of vertical magnet 33, the switch wiper 105 71 is raised opposite the second level of bank contacts. Series relay 25, upon energizing, serves to maintain its own circuit and that of vertical magnet 33 intact at armature 43 after the off normal springs have shifted, as 110 they do upon the first vertical step. At the end of the vertical movement, line relay 23 comes to rest in an energized condition and series relay 25, being short circuited, deenergizes after an instant and at armature 43 115 shifts the operating circuit from the vertical to the rotary magnet.

The calling subscriber now operates his calling device in accordance with the second and last digit in the desired number, which, 120 it will be assumed, is 5 in the present instance, whereupon the line relay 23 deenergizes a corresponding number of times. Each time armature 39 breaks away from its working contact and before it comes into engagement with its resting contact, release relay 24 is held up over the following circuit: ground, armature 54 and its resting contact, relay 24, armature 41 and its working contact, normally open contacts controlled by off normal 125 130

spring 37, armature 43 and its resting contact, relay 26, and rotary magnet 34 to battery. Rotary magnet 34 and relay 26, however, are not energized at this time on account of the high resistance of relay 24. When armature 39 comes into engagement with its resting contact, relay 24 is short circuited, whereupon rotary magnet 34 energizes. Also, relay 26 energizes in series with rotary magnet 34. Each time armature 39 breaks away from its resting contact rotary magnet 34 deenergizes. Relay 26, however, being slow to release remains energized in series with rotary magnet 34 and retains its armature attracted throughout the rotary movement. By the operation of rotary magnet 34, the wiper 71 is rotated step by step into engagement with the contact 72 which is connected with the signaling conductor of the called substation E. As a result of the energization of relay 26, a circuit is closed for ring starting relay 27 at armature 44, while the ringing circuit is opened at armature 45, thus rendering it inoperative during rotation. Relay 27, upon energizing, closes a locking circuit for itself by way of off normal spring 36 at armature 47; prepares an energizing circuit for relay 29 and slow to release relay 31 in parallel at armature 46; and closes a circuit for vibrator 142 of the power equipment P of Fig. 2, at armature 48, the operation of which will be explained hereinafter.

At the end of the rotary movement, the relay 26 deenergizes and closes the circuit for relays 29 and 31 at armature 44; and closes the signaling circuit for the called substation E at armature 45. The bell at the called substation is rung by a series of discharge kicks from an impedance coil (to be explained hereinafter) over the signaling circuit which may be traced from battery by way of impedance coil 143 and its bridged condenser, conductor 67, resting contact and armature 51, resting contact and armature 45, armature 56 and its resting contact, conductor 70, wiper 71, bank contact 72, conductor 65, bell and condenser of substation E, line conductor 21, to working contact and grounded armature 57, which armature is now in attracted position due to relay 31 having energized. The signaling circuit is completed to direct ground instead of through the lower winding of line relay 23 to improve the ringing. Relay 29, upon energizing, attracts its armature 52 but, due to being weighted, armature 52 is slow to pull up which controls the length of the ringing period. When armature 52 finally pulls up a circuit is closed for ring cut-off relay 30 by way of armature 50 and its grounded resting contact. Relay 30, upon energizing, closes a holding circuit for relay 32 at armature 53; opens the signaling circuit at armature 56; and opens the circuit of release relay 24 at armature 54. Release relay

24, upon deenergizing, closes a circuit for release magnet 35 by way of off normal spring 36 at armature 42, whereupon said magnet energizes to restore the wiper 71 to normal position. When the wiper 71 reaches normal position, the shaft of the switch shifts the off normal springs 36 and 37, whereupon the circuits of release magnet 35 and relay 27 are opened. Relay 27, upon deenergizing, opens the circuits of relays 29 and 31, whereupon they deenergize; and opens the circuit of vibrator 142, whereupon it discontinues its vibratory operation. Relay 31, upon deenergizing, removes direct ground from line conductor 21 and switches it through the double wound line relay 23 to improve transmission. Relay 29, upon deenergizing, opens the circuit of relay 30, whereupon said relay deenergizes to prepare the ringing circuit; open the circuit of relay 32; and again close the circuit of relay 24 at armature 54. Relay 32, being slow to release, will hold up until relay 24 energizes to close a circuit for the former relay at armature 40.

When the subscriber at station E responds to the ringing of his bell by removing his receiver, his telephone is connected across the common talking line, whereby he and the calling subscriber A may now converse with each other as desired.

If the subscriber at station E does not respond to the first ringing of his bell, the subscriber at station A may ring it a second time, or as many times as he desires, by redialling the number, with his receiver off, as in the first instance: when the same operation takes place as already described. At the end of the ensuing conversation, both subscribers replace their receivers, whereupon line relay 23 deenergizes and opens the circuit of release relay 24 at armature 39. Relay 24, upon deenergizing, opens the circuit of start relay 32 at armature 40, whereupon said relay deenergizes to stop the motor generator set as will be explained hereinafter. The common talking line and connector switch H have now been restored to normal condition and are ready for use over again.

An explanation of the operation of the power equipment P will be given now. When start relay 32 of the connector H energizes, a locking circuit for itself is closed at armature 59 which may be traced from ground, resting contact and armature 144, conductor 69, armature 59 and its working contact, and relay 32 to battery; and a circuit for the motor generator set is closed at armature 58 which may be traced from the commercial current source, conductor 131, the motor, conductor 64, working contact and armature 58, conductor 62, conductor 96, and conductor 132 to the other side of the commercial current source. The motor-generator set is started to operate and builds up until the generator reaches an E. M. F. of 30 volts or slightly

over, whereupon relay 141 energizes over a circuit including its top winding and resistance 147. Relay 141, upon energizing, opens the locking circuit of start relay 32 at armature 144, which serves to prevent while closed a rapid flashing of the switchhook from opening the motor circuit before it develops sufficient speed; and connects the generator in parallel with battery B at armature 145. When this latter circuit is closed the generator takes over the entire load of the switchboard and serves to reverse the current through the dry-cells and prolong their life. The twenty dry-cell battery B of approximately 30 volts, serves to furnish current for the switchboard during the building up of the generator and kills generator noise.

As a further result of the energization of start relay 32 a circuit is closed for busy lamp L at armature 75 which may be traced from the commercial current source, conductor 131, conductor 97, busy lamp L, conductor 76, armature 75 and its working contact, conductor 62, conductor 96, and conductor 132 to the other side of the commercial current source. The lamp L lights over the above traced circuit and remains lighted as long as a receiver is off the switchhook. The lamp may be mounted on the ceiling or in some other conspicuous place to serve as a busy signal for the stations on the common line.

When start relay 32 of the connector H de-energizes, the circuits of the busy lamp L and the motor generator set are opened, whereupon the busy signal is extinguished and the generator dies down. When the generator gets below the current output of the battery B the current is reversed in the lower winding of relay 141, which now opposes the current in the upper winding and causes the relay to deenergize, thus acting as a circuit breaker and restoring the switchboard current supply equipment to normal condition.

When armature 48 of relay 27 of the connector H is attracted, a circuit may be traced from ground and the working contact of said armature, conductor 66, and vibrator 142 to battery. The vibrator 142, upon energizing, attracts the pendulum 146 and upon its inward swing the reed engages a contact which short circuits the winding of the vibrator, whereupon said vibrator deenergizes and allows the pendulum to swing outward again and close an energizing circuit for the impedance coil 143. The impedance coil energizes and the condenser bridged across its winding stores up current so that an inductive kick is sent out over the signaling circuit to operate a biased bell, when the above energizing circuit of impedance coil 143 is opened. The alternate operation of the vibrator and impedance coil produces the desired signaling current.

It will be assumed now that one of the subscribers on the common line, whose telephone is A, wishes to converse with the subscriber,

whose telephone is E, but is unable to raise him by calling his regular telephone number 25 as described hereinbefore. He therefore decides to call him by means of his code number, which is 05, it being further assumed that the line is idle when the call is originated. In order to do this, the party at telephone A removes his receiver and then dials the code call number of the party at telephone E.

When the receiver is removed at telephone A, the line relay 23, release relay 24, and starting relay 32 of connector H energize in the hereinbefore described manner to prepare the connector switch for operation, light the busy lamp, and start the motor-generator set operating.

When the calling party at telephone A operates his calling device in accordance with the first digit 0 of the code number, the connector H operates in the hereinbefore described manner to raise the wiper 71 opposite the tenth level of bank contacts. As the wiper reaches the tenth level, the shaft of the switch strikes the spring 38 and closes a circuit for relay 28, which relay energizes to disconnect the wiper 71 from the source of signaling current and connect it to ground at armature 51; and to prepare a starting circuit for code call machine CC at armature 49.

When the calling party operates his calling device in accordance with the second and last digit, 5, of the code number, the connector H operates in the hereinbefore described manner to rotate the wiper 71 in to the fifth contact, or the one indicated as 73, thereby placing ground on the sixth and eighteenth contact of the left hand bank of the code call machine CC by way of conductor 74. The relay 27 energizes and locks up as before to start and hold the vibrator 142 in operation, which, however, performs no useful function at this time; to prepare circuits for relays 29 and 31; and to further prepare the starting circuit for code call machine CC. When the relay 26 finally deenergizes, circuits are closed as before for relays 29 and 31, whereupon they energize, but they perform no useful function at this time. Relay 30 is prevented from operating at this time due to the operation of relay 28.

As a further result of the deenergization of relay 26 a circuit is closed for slow acting relay 82 of the code call machine CC at armature 44, which may be traced from grounded armature 44 and its resting contact, armature 46 and its working contact, armature 55 and its resting contact, working contact and armature 49, conductor 63, wiper 87, armature 90 and its resting contact, to relay 82 and battery. Relay 82, upon energizing, closes a circuit for slow acting relay 83 at armature 92, whereupon said relay energizes and closes a circuit for motor magnet 85 at armature 93. Motor magnet 85, upon energizing, opens the circuit of relay 82 at armature 90, whereupon

said relay deenergizes and opens the circuit of relay 83. Relay 83, upon deenergizing, opens the circuit of motor magnet 85, whereupon said magnet deenergizes and causes the 5 wipers 86 and 87 to take one step to the first contacts in their respective banks. When the wiper 86 reaches the first contact a circuit is closed for relays 80 and 81 in series, whereupon they both energize and become locked 10 up by way of armature 89 of the latter. As a further result of the energization of relay 81, a circuit is prepared for double coil magnet 84 at armature 88. When the wiper 87 reaches the first contact, it encounters ground, 15 whereupon the relay 82 again energizes, this time closing a circuit for double coil magnet 84 at armature 91, in addition to closing the circuit for relay 83. Magnet 84, upon energizing, closes a circuit for the code call bells 20 98, 99, etc., at armature 94, which may be traced from the commercial current, conductor 131, conductor 97, working contacts of armature 94, conductor 95, through the bells 98, 99, etc., conductor 96, conductor 132, to the 25 commercial current. The bells 98, 99, etc., ring continuously until their circuit is broken by armature 94 falling away, which it does when magnet 84 deenergizes as a result of its circuit being opened at armature 91 when 30 relay 82 again deenergizes.

As a result of the alternate energization and deenergization of relays 82, 83 and magnet 85 due to all contacts but the last of the right hand bank being grounded, the wipers 35 86 and 87 are rotated step by step, and the code call bells are given a ring upon each step. When, however, the wiper 86 reaches the sixth contact, which contact was grounded by the connector H, relay 81 is short circuited, 40 whereupon it deenergizes to open the circuit of relay 80 at armature 89; and to open the energizing circuit of magnet 84 at armature 88. The wipers 86 and 87 continue their step-by-step rotation under control of the relays 45 82, 83 and magnet 85, but the code call bells cannot ring due to the operating circuit of magnet 84 being open at armature 88. From this it will be seen that the code call bells are given five rings, which is the code call as- 50 signed to the subscriber E.

When the wiper 86 reaches the thirteenth contact, relays 80 and 81 are again energized in series, whereupon the code call bells are again rung a series of five times, as the 55 switch continues its step by step movement. When the eighteenth contact is reached the ringing is again cut off in precisely the same manner as already explained. The wipers continue to rotate, but without effect until 60 wiper 86 reaches the twenty-fourth or next from last contact, when a circuit is closed for relay 30 which may be traced from ground, relay 81, wiper 86, conductor 61, working contact and armature 50, armature 52 and its 65 working contact, and relay 30 to battery.

Relay 81 will not energize in series with relay 30, due to the high resistance of the latter. Relay 30, upon energizing, closes a holding circuit for relay 32 at armature 53; opens the original energizing circuit of relay 82 at armature 55; and opens the circuit of release relay 24 at armature 54. Release relay 24, upon deenergizing, closes the circuit of release magnet 35, whereupon the shaft of the switch carrying the wiper 71 is restored to 70 normal position as previously explained. The shaft, in restoring, opens the off normal springs 36, 37 and 38 in the well known manner, whereupon relays 27 and 28 deenergize; thus disconnecting the vibrator 142 and 75 changing the connector H to talking condition as also previously explained. When the wipers 86 and 87 rotate to the twenty-fifth or last contact of the banks, wiper 87 no longer finds ground, whereupon relay 82 is prevented 80 from energizing and the machine CC comes to rest in what may be called home position, 85 and is ready for use over again.

When the called subscriber hears his code number sounded, he proceeds to the nearest 90 telephone on the common line and by removing the receiver, whereupon his telephone is connected across the talking line, he and the calling subscriber A may now converse with each other as before. If, however, the called subscriber does not respond to the first double 95 ringing of his code number, the subscriber at station A may cause the double ringing a second time, or as many times as he desires, by re-dialling the number with his receiver off, 100 as in the first instance; when the same operation takes place as already described.

At the end of the ensuing conversation both subscribers replace their receivers, whereupon 105 the connector H and power equipment P are restored to normal as already explained and they, as well as the common line, are ready for use again.

An explanation will now be given of the direct line system, and for this purpose it will 110 be assumed that the subscriber at station A' desires to call the subscriber at station E' without using the common talking line. In order to do this, the subscriber at station A' merely removes his receiver, whereupon the 115 line and battery feed relays 104 and 105 of the relay group R energize over a circuit which may be traced from ground, lower winding of relay 105, lower winding of relay 104, resting contact and armature 110, line conductor 101, transmitter and receiver of the bridged calling line A', line conductor 102, armature 109 and its resting contact, 120 top winding of relay 104, and top winding of relay 105 to battery. Relay 105, 125 upon energizing, closes a circuit by way of armature 119 and its resting contact, for vibrator 142 at armature 117, which starts it operating as already explained; and closes a circuit for starting relay 107 at armature 130

116. Relay 107, upon energizing, locks up to ground on the back contact of the circuit breaker 141 at armature 121, by way of the resting contact and armature 60, and closes a 5 circuit for the motor-generator set at armature 122, whereupon the motor generator set starts operating as has been already explained. Relay 104, upon energizing, prepares the talking circuit at armatures 112 and 10 115; and disconnects the line conductors 123 and 124 from line relay 103 at armatures 113 and 114, respectively, and further prepares the talking circuit as well as connects up the ringing circuit which may be traced from 15 ground, lower winding of ring cut-off relay 106, resting contact and armature 120, working contact and armature 114, line conductor 124, condenser and bell bridged across the line at substation E', line conductor 123, armature 113 and its working contact, armature 118 and its resting contact, and impedance coil 143 with the condenser in bridge of its winding to battery. The biased bell at the called subscriber's telephone E' continues 20 ringing over the above traced circuit as long as the calling subscriber A' holds his receiver off the switchhook, the latter receiving a ringing tone by way of condenser 125.

When the subscriber at station E' responds 30 to the actuation of his bell by removing his receiver, a direct current bridge is placed across the line, whereupon the ring cut-off relay 106 energizes and locks up to ground at working contact and armature 117, by way of 35 armature 119 and its working contact, and at the same time opens the circuit of the vibrator to discontinue its operation. As a further result of the energization of relay 106, the signaling circuit is broken and the talking circuit established at armatures 118 and 120, the latter circuit being shown by the heavy conductors. The subscribers may now converse with each other as desired.

At the end of the ensuing conversation, both 45 subscribers replace their receivers. When the receiver at E' is replaced, nothing happens, but when the receiver at A' is replaced the direct current bridge is replaced by the condenser and bell, whereupon relays 104 and 50 105 deenergize. Relay 104, upon deenergizing, restores the line conductors to their original condition; while relay 105, upon deenergizing, opens the locking circuit of relay 106, and opens the circuit of relay 107. 55 Relay 106, upon deenergizing, further opens the talking circuit and prepares the signaling circuit; while relay 107, upon deenergizing, opens the circuit of the motor-generator set, thus allowing it to restore to its normal 60 operative condition. The direct line is now fully restored and ready for use over again.

If the subscriber at the station E' does not respond to the actuation of his bell, the subscriber at station A' merely replaces his receiver, whereupon the relay group R is re-

stored to normal and the power equipment P is disconnected as has already been explained.

Should the subscriber E' originate the call instead of the subscriber A', practically the same operations will take place as described 70 when A' originated the call. In fact, the only difference lies in the fact that line relay 103 energizes instead of line relay 104 to close the signaling circuit and prepare the talking circuit. 75

Having described my invention, what I consider to be new and desire to have protected by Letters Patent will be pointed out in the appended claims.

What is claimed is:

1. In a telephone system, the combination with a common talking, selective signaling system providing with a line having a plurality of subscribers' stations thereon, of a direct line system accessible to two subscribers of said common line, a source of signaling current, automatic means controlled over said common line for signaling with said current any subscriber thereon individually, automatic means responsive to the lifting of a receiver on said direct line for signaling with said current the other subscriber thereon, and automatic means responsive to the lifting of said other subscriber's receiver for stopping said signaling and connecting up said subscribers for talking. 90

2. A telephone system comprising two stations normally disconnected, a central source of talking current, a central source of signaling current, means responsive to the removal of the receiver at either station for connecting said signaling current source to the line of the other station, and means for cutting off said signaling source and for closing the talking circuit when the receiver is removed at 100 the station called. 105

3. In a telephone system, a plurality of stations, a common conductor connected to said stations for supplying talking and signaling currents to said stations, a retard coil, and means whereby said coil is included in circuit with said conductor while the same is used for supplying talking current but not while it is used for supplying signaling current. 110

4. In a telephone system, a plurality of stations, a common conductor connected to said stations for supplying talking and signaling currents to said stations, a retard coil normally in circuit with said conductor, and means for open circuiting said coil while the conductor is in use for supplying signaling current. 120

5. In a telephone system comprising a party line, said line terminating in an automatic switch, individual signaling conductors terminating in a portion of the bank of said switch and extending to the several stations on said line, a code call machine, and conductors for controlling said machine termi- 125 130

- nating in another portion of the bank of said switch.
6. In a code call system, a code ringing machine, a directive switch for selecting a 5 code and for starting said ringing machine, and means responsive to the generation of two successive code signals for releasing said switch and for stopping the ringing machine.
7. In a telephone system comprising a single 10 line having a plurality of stations thereon, a central source of talking current comprising a motor generator, means for starting said motor generator whenever any station uses the line, and a single signal actuated while the 15 motor is running and serving as a busy signal to said stations.
8. In a telephone system, a plurality of stations, an electric generator, means operated responsive to the initiation of a call from any 20 station to start the generator and responsive to the termination of the call to stop it, and means for rendering the stopping means ineffective while the generator voltage is below a predetermined voltage.
- 25 9. In a telephone system, a plurality of stations, an electric generator, an electric motor for driving the same, means operated responsive to the initiation of a call from any station to start the motor and responsive to the 30 termination of the calls to stop the motor, and means for preventing the stopping of the motor before the generator reaches a predetermined voltage.
10. In a telephone system, a plurality of 35 stations, a generator, means operated responsive to the initiation of a call to start the generator, means for maintaining the generator in operation, and means operated when the generator reaches a predetermined voltage 40 to render the operation of the last named means dependent upon the continuation of a call.
11. In a telephone system, a plurality of 45 stations, a source of electromotive force including a battery and a generator, means for operating the generator, means for connecting the generator in parallel with the battery when the generator electromotive force becomes slightly greater than the battery electromotive force, means operated from the 50 battery responsive to the initiation of a call to cause the first named means to operate, and operated responsive to the cessation of a call to cause the first named means to stop the generator if the second named means has 55 operated.
12. In a telephone system, a station, a 60 switch having a plurality of contacts, means whereby said station may automatically operate the switch to select a desired contact, a code call machine associated with said contacts, means for automatically operating the code call machine responsive to the selection of a contact, said machine including means for repeatedly sending out a code corresponding to the contact selected, and means for automatically stopping the code call machine after the code has been sent out a predetermined number of times.
13. In a telephone system, a plurality of 65 stations each having ringing means, a switch having a number of contacts each of which is associated with the ringing means of a different station, additional contacts on the switch, a code call machine associated with 70 said last mentioned contacts, means whereby any station may automatically operate the switch to select any contact, means for operating the code call machine responsive to the selection of a contact associated therewith, said machine including means for repeatedly sending out a code corresponding to the contact selected, and means for automatically stopping the code call machine after the code 75 has been sent out a predetermined number of times.
14. In a telephone system, a plurality of 80 stations on a party line, each station having ringing means, an automatic switch accessible to all of said stations, a code call machine, means for operating said switch from any of said stations to individually signal any other station or to operate the code call machine, common signalling means, and means effective if the code call machine is selected for transmitting one of a plurality of 85 code signals to the common signalling means, the particular code transmitted being determined by the particular setting of the switch.
15. In a telephone system, a plurality of 90 stations on a party line each station having ringing means, a switch having two groups of contacts each of the contacts of one of the groups being associated with the ringing means of a different one of the stations, a code call machine associated with the contacts of the second group, means whereby the 95 switch may be operated from any station to select any contact, means responsive to the selection of a contact in the first mentioned group for operating the ringing means of the particular station associated with the selected contact, a common signalling apparatus, and means responsive to the selection of any contact in the second group for operating the 100 code call machine for transmitting a particular one of a plurality of codes to the signalling apparatus, the particular code being determined by the particular contact selected.
- In witness whereof, I hereunto subscribe 105 my name this 6th day of May, A. D., 1925.
- CLARENCE E. LOMAX.
